UNITED STATES PATENT OFFICE.

ROBERT CUNNINGHAM, OF CHICAGO, ILLINOIS.

IMPROVEMENT IN DEVICES FOR MAKING WATER-TRAPS.

Specification forming part of Letters Patent No. **139,946**, dated June 17, 1873; application filed March 10, 1873.

To all whom it may concern:

Be it known that I, ROBERT CUNNINGHAM, of Chicago, in the county of Cook and State of Illinois, have invented a new and Improved Device for Making Lead or Composition Water Traps and Bends; and I do hereby declare the following to be a full description thereof, reference being had to the accompanying drawings making a part of this specification, in which—

Figure 1 represents the device to be attached to a reservoir holding the hot lead or composition to be forced through the die B B, by any suitable power, (said reservoir not shown in the drawings.) A A represent the diaphragm, to be moved to either side by any suitable means. Fig. 2, A A represent the perforated diaphragm removed. Fig. 3 represents the die B B, the movable diaphragm A A, and the mandrel C supported by the wings D D D.

The nature of my invention consists in a device by means of which lead or composition, in being forced through a die and around a mandrel, is graduated and controlled in its passage by a movable perforated diaphragm or gage, so that the quantity of lead or composition is increased or diminished on either side alternately, whereby it assumes any de-

sired curve, and is thus formed into a trap or bend of uniform size and thickness in every part.

When in use, if the diaphragm A A is in the center, the lead or composition will pass out in the form of a straight pipe. By moving the diaphragm A A to one side it will reduce the amount of lead or composition passing out on that side, and allow it to pass out on the other side, forming a curve. Then, by moving the diaphragm A A back to the center, the composition will pass out as before in the form of a straight pipe. Now, move the diaphragm A A to the opposite side and it will reduce the amount of lead or composition passing out on that side and allow it to pass out on the other side, and form a curve the reverse of the first, and by again moving the diaphragm A A to the center it will allow the lead or composition to pass out, forming a straight pipe.

What I claim as new is as follows:

The combination of the diaphragm A A, or its equivalent, with the die B B and mandrel C, constructed and operated substantially as set forth.

ROBERT CUNNINGHAM.
